Des. 214,034
Patented May 6, 1969

214,034

FEATURE STRIP

James L. Griffith, Dallas, Tex., assignor to H. H. Robertson Company, Pittsburgh, Pa., a corporation of Pennsylvania

Filed May 27, 1968, Ser. No. 12,095

Term of patent 14 years

Int. Cl. D25—03

U.S. Cl. D13—6

Fig. 1

Fig. 2

Fig. 3

Fig. 4

FIGURE 1 is a transverse sectional view of my design for a feature strip.

FIGURE 2 is a plan view of a length of the feature strip, viewed in the direction of arrow 2 of FIGURE 1, but on a reduced scale.

FIGURE 3 is a side view of a length of the feature strip, viewed in the direction of arrow 3 of FIGURE 1, but on a reduced scale.

FIGURE 4 is a side view of a length of the feature strip, viewed in the direction of arrow 4 of FIGURE 1, but on a reduced scale.

The upper end of the feature strip is shown fragmentarily to indicate an article of indefinite length.

I claim:

The ornamental design for a feature strip, as shown and described.
